CLAIM

The ornamental design for a dishrack wineglass holder, as shown and described.

DESCRIPTION

FIG. 1 is a perspective view of a dishrack wineglass holder showing our new design, with the dishrack shown in phantom lines to illustrate environment and not forming a part of the new design;

FIG. 2 is front perspective view of the dishrack wineglass holder of our new design;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.
